(57) **CLAIM**

The ornamental design for a catheter securement device, as shown and described.

DESCRIPTION

FIG. 1 is a perspective view of a catheter securement device in accordance with an embodiment of the present design; FIG. 2 is a bottom perspective view of the securement device of FIG. 1;

FIG. 3 is a top plan view of the securement device of FIG. 1; FIG. 4 is a bottom plan view of the securement device of FIG. 1;

FIG. 5 is a back elevational view of the securement device of FIG. 1;

FIG. 6 is a front elevational view of the securement device of FIG. 1;

FIG. 7 is a left-side elevational view of the securement device of FIG. 1;

FIG. 8 is a right-side elevational view of the securement device of FIG. 1;

FIG. 9 is a perspective view of the securement device of FIG. 1 with a catheter shown in dashed lines within a recess; and, FIG. 10 is a perspective view the securement device positioned on an arm of a patient with a catheter in accordance with an embodiment of the present design.

The elements shown in dashed lines form no part of the claimed design.

1 Claim, 4 Drawing Sheets
